UNITED STATES PATENT OFFICE.

SAMUEL LLOYD, OF ARRINGTON, VIRGINIA.

CLOTHES-PIN.

1,067,931.

Specification of Letters Patent. Patented July 22, 1913.

Application filed October 26, 1912. Serial No. 727,873.

To all whom it may concern:

Be it known that I, SAMUEL LLOYD, a citizen of the United States, residing at Arrington, in the county of Nelson and State 5 of Virginia, have invented certain new and useful Improvements in Clothes-Pins, of which the following is a specification.

My invention relates to an improvement in clothespins, and the object is to provide 10 a device which can be applied directly to the clothes line and which is capable of a sliding or rotary movement upon the clothes line.

This invention consists of certain novel 15 features of construction and combinations of parts which will be hereinafter more fully described and pointed out in the claim.

In the accompanying drawings—Figure 1 is a view in perspective of the invention as 20 applied to the line; Fig. 2 is a cross sectional view. Fig. 3 is a top plan view of the wire portion of the clothes pin.

A represents the clothes line.

B is a sheet metal clamp folded into U 25 shape in cross section and adapted to rest astride the clothes line, upon which it is held by a thumb bolt 2 passing through holes in the clamp, and on the threaded end of which a nut 3 is screwed. It is thus possible to place the clamp upon the clothes line 30 at any point by simply removing the thumb bolt or before same is inserted, after which it is screwed into the nut loosely if it is desirable to slide the clamp or tightly if the 35 clamp is to be fixed at a given point on the line. Thus the clamp may be held in place permanently, to all intents and purposes, or slidably, it being retained upon the line so long as the thumb bolt and nut are 40 screwed together, although of course it might be removed at any time if desired by removing the thumb bolt and screw and lifting the clamp from the line. Two spring arms 7—7 are rigidly held by the clamp.

These spring arms are preferably made of 45 a single wire, which are bent approximately as illustrated, extending upwardly in opposite directions from the center, where they are securely held by the crimps 4—4 in the edges of the clamp. The extreme outer 50 ends of the wire forming the arms are twisted together and adapted to be held astride the clothes line with a downward pressure against the clothes, due to the action of the four coiled springs 6—6 formed along the 55 wire at the outer ends of the clamp. To facilitate raising the arms, the eyelets 5—5 are formed at the free outer ends of the arms.

By means of the foregoing construction, 60 a simple device is afforded for fastening the clothes upon a line without injuring the clothes or without any danger of the fastening means becoming accidentally displaced, they being, to all intents and purposes, 65 permanently, though slidably, mounted upon the line.

Having thus described my invention what I claim as new and desire to secure by Letters Patent is—

As an article of manufacture, a clothes pin comprising an approximately U-shaped clamp adapted to receive the clothes line through the open side thereof, removable means extending transversely through the 75 clamp adapted to close the open side of the latter and fasten the clothes pin upon the line against accidental displacement, and spring arms rigidly secured to the edges of the clamp and resting astride the line with 80 a spring pressure upon the latter.

In testimony whereof I affix my signature. In the presence of two witnesses.

SAMUEL LLOYD.
